UNITED STATES PATENT OFFICE.

JAMES PRIESTNALL NAYLOR, OF LONDON, ENGLAND.

SOCKET STRUCTURE FOR ELECTRIC INCANDESCENT LAMPS.

1,089,343.

Specification of Letters Patent.

Patented Mar. 3, 1914.

Application filed January 10, 1914. Serial No. 811,386.

To all whom it may concern:

Be it known that I, JAMES PRIESTNALL NAYLOR, a subject of the King of England, residing at London, in England, have invented certain new and useful Improvements in Socket Structures for Electric Incandescent Lamps, of which the following is a specification.

This invention relates to a socket structure for electric incandescent lamps, more particularly for use in cases where a plurality of said lamps are connected in series such for example in electric advertising or signaling apparatus in which letters or signs are exhibited by a suitable arrangement of such a plurality of lamps.

A plurality of electric lamps have been previously mounted in series or parallel in such a manner that on failure of, or removal of, a lamp an alternative circuit or substitutional resistance is automatically produced, but with all constructions known to me it has been necessary to provide some auxiliary means, electromagnetic or otherwise, for bringing the said alternative circuit or substitutional resistance into operation. Now according to the present invention this production of the alternative circuit or insertion into the circuit of the plurality of lamps is effected direct without the intervention of any auxiliary means outside the lamp socket structure on removal of the lamp by the provision of a novel construction of lamp contacts in such a manner that after or during the withdrawal of any lamp the circuit may be maintained, due to said contacts being permitted to engage one another, or to engage a third contact connected to a resistance, thus providing an alternative circuit.

In the case of a monogrammic or similar advertising apparatus with a series of electric lamps in operation, the removal of one of said lamps from the circuit would cause the remainder of the series to be extinguished and without the short circuiting means referred to above it would not be possible to arrange and rearrange a number of lamps upon a monogram to form a letter or sequence of dissimilar letters requiring varying numbers of elements or lamps, since when a letter is formed upon a monogram, there are always some positions or sockets unoccupied so that without the substitutional path or circuit these positions would constitute a discontinuity or interruption of

the circuit and the insertion of a lamp in an unoccupied position will separate the contacts and render inoperative the alternative circuit so that the current must then flow through the lamp filament in substitution of the alternative circuit.

The invention consists in the novel features, arrangements and combinations of parts hereinafter fully described and specifically pointed out in the appended claim, reference being directed to the accompanying drawings, in which—

Figure 1 is a section illustrating one embodiment of the present invention. Fig. 2 a section illustrating a modification with the use of a resistance in the substitutional circuit; and Figs. 3 and 4 are partial views of sockets shown in Figs. 1 and 2, with the lamps removed, showing closed circuits.

Figs. 1 and 3 illustrate part of a solid panel or other support G and a lamp or "element" inserted through an aperture N therein. A represents an electric incandescent lamp, B a tubular extension of or an addition to the lamp cap, connected with one end of the filament, C is a tubular section of insulating material inserted in the tube B, and D is a smaller concentric conductor passing down the insulated tube C and connected to the opposite end of the lamp filament, such member having a conducting ball or enlargement E attached to its end. Attached to the rear of the support G are two resilient contacts H¹ and I¹ arranged to engage respectively with the sections B and E of the element, when the lamp base is passed through the aperture N, the said contacts being fed by electric conductors P and Q which are connected to other similar contacts of further elements upon the support so that the whole of the resilient contacts H¹ and I¹ are connected in electrical series. Now when the portion B D E, of the element is inserted as shown, the contact H¹ is lifted so that it ceases to engage the contact I¹ and the lamp filament is then substituted for the alternative path or circuit H¹, I¹.

In the construction shown in Figs. 2 and 4 I provide the lamp receiving socket G¹ with an additional contact H² and each is provided with a resistance R, equivalent to the resistance of the lamp element, and connected therewith as by the conductors R¹ so that the removal or replacement of a lamp forming one of a series does not affect the

total resistance of the circuit. If the conductors X Y are connected with a source of electricity and an element is inserted in the face of the monogram or socket, current will flow through the conductor X to the contact H¹ thence to the element contact tube B through the filament of lamp A to the point E then through resilient contact I¹ to the opposite pole of a source of electricity. When the element is removed the contact I¹ engages the additional contact tongue H² so that if the conductors X Y remained connected to the source of electricity, current will now flow through the conductor X to the conductor R¹ through the resistance R to the contact tongue H² which engages contact I¹ and thence to conductor Y, so that the resistance R is automatically cut into circuit, as shown in Fig. 4. When said lamp is inserted in the contacts the circuit to the resistance R is opened so that current then has a path through the lamp filament, as described. It will be seen that if the whole of the element retaining positions are connected in series, series-parallel or in parallel, and constructed in this manner, any number of elements containing electric lamps may be inserted in the provided holders or withdrawn therefrom without materially affecting the current flowing in the said series of parallel circuits. It is desirable that the contacts H¹, H², I¹, should be so constructed that the current has an alternative path through the electric lamp filament before it opens the contact H², thus preventing injurious sparking occurring at this point, as might be the case in series working. Fig. 2 also illustrates the construction adopted when the background is not continuous but is formed for example, of open wirework, or a network composed by a spilection of links. The body G¹ forming the socket has the lugs G² for attachment of the wires whereby it is connected to other sockets in proper relative location. G³ is a threaded cap for closing the back of the socket G. The lamp is shown as having a circular plate F attached to its cap, such cir-

cular plate being preferably of dissimilar color or material to the front of the support so as to form the daylight member, and the said lamp plate, lamp cap, and concentric connection members collectively form the element. A domed cover or globe F¹ of transparent or translucent material is also shown as connected to the plate F and covering the lamp A.

What I claim as my invention and desire to secure by Letters Patent of the United States is:—

1. In a socket structure for incandescent lamps, the combination of a pair of lamp-engaging contacts, a third contact arranged to engage one of said lamp-engaging contacts when a lamp is absent and to be disengaged therefrom on insertion of a lamp, and an electrical connection between said third contact and the other lamp-engaging contact.

2. In a socket structure for incandescent lamps, the combination of a pair of lamp-engaging contacts, a third contact arranged to engage one of said lamp-engaging contacts when a lamp is absent and to be disengaged therefrom on insertion of a lamp, and a resistance between said third contact and the other lamp-engaging contact, said resistance substantially equal to the resistance of a lamp filament normally inserted in said socket.

3. In a socket structure for incandescent lamps, the combination of a pair of lamp-engaging contacts, a circuit connection between the contacts including a resistance equal to that of a lamp, and circuit-closing means in said circuit connection operable by the lamp to open the circuit by insertion of the lamp and closing the same when the lamp is removed.

In witness whereof I have signed this specification in the presence of two witnesses.

JAMES PRIESTNALL NAYLOR.
